UNITED STATES PATENT OFFICE.

ALBERT G. SCHERER, OF CHICAGO, ILLINOIS, ASSIGNOR TO EXCELSIOR STEEL FURNACE COMPANY, OF CHICAGO, ILLINOIS, A CORPORATION OF ILLINOIS.

ADJUSTABLE HOT-AIR BOOT.

1,209,043.

Specification of Letters Patent. Patented Dec. 19, 1916.

Application filed October 5, 1916. Serial No. 123,897.

To all whom it may concern:

Be it known that I, ALBERT G. SCHERER, a citizen of the United States, and a resident of the city of Chicago, county of Cook, and 5 State of Illinois, have invented certain new and useful Improvements in Adjustable Hot-Air Boots, of which the following is a specification.

In hot-air heating it is the usual practice 10 to run round pipe from the furnace to pipe of rectangular section installed between the studding in the walls of the building to be heated. The boot is the fitting or section of conduit which serves to make the connection 15 between the pipe of round and rectangular section. The width of studding is different in different buildings, which, together with variation in register sizes, creates a demand for pipe of rectangular section of different 20 thickness or depth, and heretofore, so far as I am aware, it has been necessary to build and carry in stock boots with rectangular pipe connections of different thicknesses or 25 depths, each different dimension of thickness or depth of rectangular pipe connection requiring a separate stock of boots, and each dimension of boot requiring separate and different patterns.

My present object is to provide a boot the 30 rectangular pipe connection of which is capable of adjustment so that it may be adjusted to take any usual thickness or depth of pipe of rectangular section. I attain the above object by means of the structure illustrated in the accompanying drawings, in 35 which—

Figure 1 is a side elevation of a boot embodying my invention, the adjustable portion thereof in deepest or most extended position; Fig. 2 is a fragment similar to Fig. 1, the adjustable portion thereof being in thinnest or smallest position; Fig. 3 is a fragmentary section showing the adjustable side in elevation and in an intermediate position. 40 Fig. 4 is a plan of the fragment shown in Fig. 3; Fig. 5 is a section on line 5—5 of Fig. 3; Fig. 6 is a fragmental sectional view showing a modified form of closing apron. Fig. 7 is a fragmental section similar to Fig. 45 6, showing another modification of the closing apron. Fig. 8 is a fragmental elevation, showing my invention applied to a double wall boot; Fig. 9 is a section of the construction shown in Fig. 8; and Fig. 10 is a section 50 on line 10—10 of Fig. 8.

Similar reference characters refer to similar parts throughout the respective views.

As is the usual practice, the boot comprises an annular collar, 11, adapted to assemble with the pipe of circumferential section 60 coming from the furnace. Secured to and extending from the collar 11 are suitably designed pieces, 12, to taper the boot from the annular collar to the rectangular pipe connection, having the relatively long front 65 and back walls, 13 and 14, adapted to extend between the joist of a wall and the relatively short end walls, 15, adapted to face the sides of adjacent joist.

The metal of the piece or pieces, 12, is 70 carried up to form the back, 14, and ends, 15, of the rectangular pipe connection, and the back wall, 14, is provided with a strip of metal, 16, having oppositely turned edges. One turn of the strip, 16, is placed over the 75 top of the back wall, 14, and is secured in place by diagonal crimping, or in any other suitable manner, so that the strip extends downwardly from the top of the wall upon the outside thereof and its turned up lower 80 edge forms a pocket, 17, for the reception of the edge wall of the section with which it is assembled.

The portion of the tapering piece or 85 pieces, 12, which abut the front wall, 13, of the rectangular pipe connection, end at their juncture with the bottom of the pipe connection portion, and the parts of the pieces, 12, which are extended to form the ends, 15, of the rectangular pipe connection in a similar 90 manner in which the rear wall, 14, is formed, are also cut away at their forward ends, as is clearly shown in dotted lines at 18^a in Figs. 1 and 3. Upon the inner faces 95 of the end walls, 15, are secured strips, 18, by rivets, 19, which are preferably passed through the strips, 18, near their upper edges so as to permit of the bottom of the strips to be more easily sprung away from the inner faces of the end walls, 15.

The front wall of the rectangular pipe connection consists of a vertical flange, 20, of a piece of sheet metal, which is also provided with a horizontal flange or apron, 21, which serves to close the portion of the top 105 of the boot which would otherwise be left open when the front wall of the rectangular pipe connection is pushed in to adjust the connection for a thinner rectangular pipe. The vertical flange, 20, extends considerably 110

beyond the apron, 21, on either side and these extensions, 22, are considerably broader than the flange, 20. The extensions, 22, are bent at right-angles with the flange, 20, and their lower edges are bent upwardly as at 23 in Fig. 5, so as to extend under the lower edges of the strips, 18. The upper edges of the extensions, 22, are bent outwardly over the end-walls, 15, and are then bent outwardly and upwardly to form pockets, 24, to receive the end walls of the section with which they are adapted to assemble, as clearly shown in Fig. 5. The front vertical flange, 20, is provided with a strip 16^a, having a pocket, 17^a, similar in all respects to the strip, 16, having the pocket, 17, provided upon the rear wall, 14.

It will now be seen that in order to fit the boot for assembly with any but the thickest pipe of rectangular section, for which the pipe is made, it is only necessary to press in the front vertical flange, 20, the proper distance. When the front vertical flange, 20, has been properly adjusted, it may be secured in the adjusted position by turning over the exposed ends of the strips, 18, as shown in dotted lines in Fig. 4.

If the protrusion of the horizontal flange or apron, 21, be deemed unsightly, it may be extended inside of the tapering walls, as shown at 21^a in Fig. 6, in which case I prefer to provide a pocket for it by riveting a suitably shaped piece of metal, 25, to the inner face of the piece, 12. The flange or apron, 21, may also be hinged to the vertical flange, 20, so as to swing down by the wall, 12, as clearly shown at 21^b in Fig. 7.

I have heretofore described my invention as applied to single wall hot air stack, but it may be equally well applied to a double wall construction, in which case the upper edges of the extensions, 22, are not provided with pockets, 24, but terminate at the spacers, 25, between the inner and outer walls of the double walled section, as clearly shown at 26 in Fig. 10. The pocket, 17^a, is also omitted from the front vertical wall, 20, and instead the piece of metal, 16^b, is so shaped as to assemble with the edge of a double wall section, as clearly shown in Fig. 9. In the double wall construction I also secure an increased rigidity of structure by providing vertical flanges, 26^a, upon the ends of the horizontal apron, 21, which are engaged by inwardly turned lips, 27, formed upon the outer wall of the double walled section.

Having thus described my invention, it will be apparent to others skilled in this art, that divers modifications and refinements are possible without departing from the scope of the appended claims, which are as follows:

What I claim as new is:—

65 1. A boot for air conduit having a collar

adapted to receive a pipe of circumferential section, and a connection for conduit of rectangular section comprising rear and side walls, a separate piece having front and side walls, and a laterally extending apron, 70 means for slidably connecting the side walls of the separate piece with the side walls for the rectangular connection, whereby the lateral apron will cover the opening produced by the inward adjustment of the separate 75 piece.

2. A boot for air conduit having a collar adapted to receive a pipe of circumferential section, and a connection for conduit of rectangular section comprising rear and side 80 walls, a separate piece having front and side walls, and a laterally extending apron, 85 means for slidably connecting the side walls of the separate piece with the side walls for the rectangular connection, whereby the lateral apron will cover the opening produced by the inward adjustment of the sliding piece, and means for locking said sliding piece in adjusted position.

3. A connecting unit for conduit one end 90 of which terminates in a collar adapted to receive a conduit of circular section, the other end of which terminates in extensions adapted to receive conduit of rectangular section, which last-mentioned end comprises 95 stationary back and side walls, a front wall adjustably connected therewith, an apron carried by the adjustable front wall whereby the opening produced by the inward adjustment thereof will be covered by the 100 apron.

4. A connecting unit for conduit one end of which terminates in a collar adapted to receive a conduit of circular section, the other end of which terminates in extensions 105 adapted to receive conduit of rectangular section, which last-mentioned end comprises stationary back and side walls, a front wall adjustably connected therewith, an apron carried by the adjustable front wall whereby the opening produced by the inward adjustment thereof will be covered by the 110 apron, and means for locking the adjustment of the front wall.

5. A connecting unit for conduit comprising 115 rear and side walls, a separate piece having front and side walls, a laterally extending apron, means for slidably connecting the side walls of the separate piece with the side walls of the connecting unit whereby the lateral apron will cover the opening produced by the inward adjustment of the sliding piece.

6. A connecting unit for conduit comprising 125 rear and side walls, a separate piece having front and side walls, a laterally extending apron, means for slidably connecting the side walls of the separate piece with the side walls of the connecting unit whereby the lateral apron will cover the opening pro- 130

duced by the inward adjustment of the sliding piece, and means for locking the unit in adjusted position.

7. A connecting unit for conduit one end whereof terminates in stationary rear and side walls, a front wall adjustably connected therewith, an apron carried by the adjustable front wall whereby the opening produced by the inward adjustment thereof will be covered by the apron.

8. A connecting unit for conduit one end whereof terminates in stationary rear and side walls, a front wall adjustably con-

nected therewith, an apron carried by the adjustable front wall whereby the opening produced by the inward adjustment thereof will be covered by the apron, and means for locking the unit in adjusted position.

Signed at Chicago, county of Cook and State of Illinois, this 29th day of September, 1916.

ALBERT G. SCHERER.
